UNITED STATES PATENT OFFICE.

ELMER G. GARTIN, OF CLAREMONT, NEW HAMPSHIRE, ASSIGNOR TO SULLIVAN MACHINERY COMPANY, A CORPORATION OF MASSACHUSETTS.

DRILLING MECHANISM.

Application filed May 21, 1924. Serial No. 714,966.

This invention relates to drilling mechanisms.

It has for its object to provide an improved drilling mechanism. A further object is to provide an improved drilling mechanism having improved hole cleansing means. Another object is to provide improved hole cleansing means in combination with a reciprocating hammer piston. Another object is to provide an improved hole cleansing means wherein two cleansing tubes are used with improved tube supporting means. A further object is to provide a plurality of improved dependent coaxial cleansing fluid conducting tubes. 15 In the accompanying drawings I have shown for purposes of illustration one form which my invention may assume in practice.

In these drawings,—

Fig. 1 is a side elevation of a drilling motor 20 partly broken away to show details of my improved means.

Fig. 2 is an enlarged transverse section on line 2—2 of Fig. 1.

In the illustrative embodiment of my invention I have shown the same in combination with a usual type of drilling mechanism comprising a cylinder 1 having a rear head 2 and a front head 3, the latter constituting a reduced portion of the cylinder 1. Reciprocably mounted within the cylinder 1 is a usual hammer piston 4 having a striking bar 5 projecting through the head 3 to engage a usual hollow steel 6 carried by a chuck sleeve 7 rotatably mounted within a chuck housing 8 carried by the front end of the cylinder 1. The striking bar 5 has flutes 9 on the periphery thereof adapted to engage lugs formed on a chuck nut 10 fixedly carried by the sleeve 7. Projecting forwardly from the head 2 through the striking bar 5 and into the steel 6, is a hollow cleansing fluid conducting tube 11, while concentrically disposed thereto and also projecting from the rear head 2 is a gaseous cleansing fluid conducting tube 12 45 terminating within a bore 13 formed within the striking bar 5.

In order to provide an extremely simple means for supporting the inner tube 11 and still allow flow of fluid through the outer tube, a reduced portion 14 is formed on the free end of the outer tube. This reduced portion engages the inner tube 11 throughout its circumference at a point in front of ports 15 formed in the transverse or inclined portion of the tube connecting the reduced and

enlarged portions. It will thus be seen that fluid can flow from the large tube through the ports 15 and thence down into the steel 6, at the same time providing ample bearing surface for positioning and supporting the inner tube 11. It will be noted from Fig. 2 that the ports 15 are shown as three in number, but that any desired number may be used.

While I have in this application specifically described one form which my invention may assume in practice, it will be understood that this form of the same has been shown for purposes of illustration and that the invention may be modified and embodied in various other forms without departing from its spirit or the scope of the appended claims.

What I claim as new and desire to secure by Letters Patent is:

1. The combination with a drilling mechanism having a motor and a hollow drill steel actuated thereby, of hole cleansing means cooperating with said steel comprising inner and outer fluid conducting tubes, the outer of said tubes having a circumferentially extending reduced portion at its free extremity engaging the other tube throughout its circumference to support the latter tube against lateral displacement, and means permitting flow of fluid from said outer tube.

2. The combination with a drilling mechanism including a motor having a hammer piston and a hollow drill steel actuated thereby, of hole cleansing means comprising inner and outer cleansing fluid conducting tubes cooperating with said steel, the free end of said outer tube being supported by said piston and having said end depressed throughout its circumference into engagement with said inner tube for supporting the free end of the latter, and means for permitting fluid discharge from said outer tube.

3. The combination with a drilling mechanism having a motor and a hollow drill steel actuated thereby, of hole cleansing means cooperating with said steel comprising concentric fluid conducting tubes, the forward portion of the outer tube having a reduced portion engaging the inner tube completely about its periphery for supporting the latter tube, and means including ports formed in said outer tube for allowing flow of fluid from said outer tube.

4. The combination with a drilling mechanism having a motor and a hollow drill steel actuated thereby, of hole cleansing means

- cooperating with said steel comprising concentric fluid conducting tubes, the forward portion of the outer tube having a reduced portion engaging the inner tube completely about its periphery for supporting the latter tube, and means including ports formed in said outer tube opening outwardly therefrom rearwardly of said engaging portion for allowing flow of fluid from said outer tube.
10. 5. The combination with a drilling mechanism having a motor and a hollow drill steel actuated thereby, of hole cleansing means cooperating with said steel comprising concentric fluid conducting tubes, the outer tube having a depressed portion engaging the inner tube for supporting the latter, and means including ports formed in said outer tube discharging at points rearwardly of said engaging portion to permit flow of fluid laterally therefrom and externally of said depressed supporting portion.
15. 6. The combination with a drilling mechanism including a motor having a movable element and a hollow drill steel, of hole cleansing means cooperating with said steel comprising coaxial inner and outer fluid conducting tubes, the outer tube being supported at its free end by said movable element and having a reduced portion engaging the inner tube to support the latter and means including ports formed in said outer tube rearwardly of said engaging portion to permit flow of fluid laterally therefrom and externally of said reduced supporting portion.
20. 7. The combination with a drilling mechanism having a motor and a hollow drill steel actuated thereby, of hole cleansing means cooperating with said steel comprising coaxial inner and outer fluid conducting tubes, one of said tubes having a reduced portion engaging the other tube to support the latter, means for discharging fluid from said former tube, and means whereby fluid flow from said former tube passes externally over said reduced portion.
25. 8. The combination with a drilling mechanism having a motor and a hollow drill steel actuated thereby, of hole cleansing means cooperating with said steel comprising concentric fluid conducting tubes, one of said tubes having a reduced portion engaging the inner tube to support the latter, and means comprising discharge ports in said tube whereby flow of cleansing fluid is first within said tube and then longitudinally externally of an outer portion thereof.
30. 9. The combination with a drilling mechanism having a motor and a hollow drill steel actuated thereby, of hole cleansing means cooperating with said steel comprising concentric fluid conducting tubes, one of which supports the other, and means for discharging cleansing fluid laterally from the outer of said tubes intermediate the ends thereof.
35. 10. The combination with a drilling mechanism having a motor and a hollow drill steel actuated thereby, of hole cleansing means cooperating with said steel comprising concentric cleansing fluid conducting means, the forward portion of the outer one of said means having a reduced portion engaging the inner means to support the latter, and said outer means having ports disposed wholly at the rear of said reduced portion for allowing flow of fluid laterally from said outer means.
40. 11. The combination with a drilling mechanism having a motor and a hollow drill steel actuated thereby, of hole cleansing means cooperating with said steel comprising a cleansing fluid conducting tube, the forward portion thereof having an inclined inwardly projecting portion, and ports disposed within said inclined portion for allowing the flow of fluid laterally therefrom, said reduced portion being adapted to support an accessory of said drilling mechanism.
45. 12. The combination with a drilling mechanism having a motor and a hollow drill steel actuated thereby, of hole cleansing means cooperating with said steel comprising coaxially arranged inner and outer fluid conducting tubes, the forward portion of the outer tube having an inclined inwardly projecting portion engaging the inner tube to support the latter, and ports disposed within said inclined portion for allowing flow of fluid laterally from said outer tube.
50. 13. The combination with a drilling mechanism having a motor and a hollow drill steel actuated thereby, of hole cleansing means cooperating with said steel comprising coaxially arranged inner and outer fluid conducting tubes, the outer tube having a reduced portion at its forward extremity engaging the inner tube to support the free end of the latter against lateral displacement, and means including ports formed in said outer tube rearwardly of said engaging portion to permit flow of fluid laterally therefrom and longitudinally externally of said reduced portion.

In testimony whereof I affix my signature.

ELMER G. GARTIN.
